United States Patent [19]

Fechtner

[11] Patent Number: Des. 305,360

[45] Date of Patent: ** Jan. 2, 1990

[54] FLUID CARTRIDGE FOR AN AUTOMATED CLINICAL CHEMICAL ANALYZER

[75] Inventor: Harold F. Fechtner, Claremont, Calif.

[73] Assignee: Beckman Instruments, Inc., Fullerton, Calif.

[**] Term: 14 Years

[21] Appl. No.: 884,575

[22] Filed: Jul. 11, 1986

[52] U.S. Cl. D24/8; D9/347; D9/367

[58] Field of Search D9/337, 338, 347, 349, D9/352, 353, 355, 367, 368, 369, 370, 372, 373, 374, 378, 387, 390, 394, 399, 401, 403, 404, 406, 413, 428, 438; D24/1.1, 8; 220/67, 78, 75, 222/173, 181, 185; 422/102

[57] CLAIM

The ornamental design for a fluid cartridge for an automated clinical chemical analyzer, as shown.

DESCRIPTION

FIG. 1 is a perspective view of a fluid cartridge for an automated clinical chemical analyzer, showing my new design;

FIG. 2 is a right side elevational view thereof;

FIG. 3 is a front elevational view thereof;

FIG. 4 is a bottom plan view thereof;

FIG. 5 is a left side elevational view thereof;

FIG. 6 is a rear elevational view thereof.

FIG. 1

FIG. 2

FIG. 4

FIG. 5

FIG. 3

FIG. 6
